(57) **CLAIM**

The ornamental design for a compact cord lock, as shown and described.

DESCRIPTION

FIG. 1 is a perspective view of a compact cord lock.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the compact cord lock shown in condition of use with broken line environmental structure. The broken line showing of environmental structure is for illustrative purposes only and forms no part of the claimed design.
